UNITED STATES PATENT OFFICE

155,323

DESIGN FOR A GAME BOARD

Lorne E. Pogue, Long Beach, Calif.

Application December 9, 1947, Serial No. 143,067

Term of patent 3½ years

(Cl. D34—5)

To all whom it may concern:

Be it known that I, Lorne E. Pogue, a citizen of the United States, residing at Long Beach, in the county of Los Angeles and State of California, have invented a new, original, and ornamental Design for a Game Board, of which the following is a specification, reference being had to the accompanying drawing, forming part thereof.

Figure 1 is a top plan view of a game board, showing my new design.

Figure 2 is an edge view thereof.

I claim:

The ornamental design for a game board, as shown.

LORNE E. POGUE.
